(57) CLAIM

The ornamental design for a “stake head,” as shown and described.

DESCRIPTION

FIG. 1 is a top perspective view of a stake head showing my new design;

FIG. 2 is front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The broken lines in FIG. 1 are for the purpose of illustrating the environment of the design only, and form no part of the claimed design.
